PORTABLE FLUSH-TYPE COMMODE

Isadore Levin, Washington, D. C.

Application June 2, 1945, Serial No. 597,183

18 Claims. (Cl. 4—10)

1

The present invention relates to an improved multiple purpose water closet of a portable, readily available type which is such as to lend itself adaptable for ready and practical use in hospitals, clinics, sick rooms and the like, this in a manner to effectively accommodate bedridden, as well as convalescing and occasional, patients.

More specifically, and in carrying out the preferred principles of the invention, I contemplate the adoption and use of a readily maneuverable and handily operable flush-type water closet of a convertible form in that it functions to embody the needs and facilities of a bed pan on the one hand, and a stool-high, regular toilet bowl or hopper, on the other hand.

In reducing to practice a demonstrative and preferred embodiment of my inventive ideas, I have in mind the provision of a simple, expedient and practicable structural assembly incorporating such facilities as meet the needs of the user, this with the greatest degree of convenience, with a maximum of utility from a standpoint of adaptability and safety, and with a minimum of inconvenience and embarrassment to all concerned.

Stated with greater particularity, and briefly and comprehensively visualized, the structure adopted comprises a readily rollable and shiftable carriage characterized by a base, a vertically liftable and lowerable especially designed bowl supported on and above the base, a pedestal-like stand on the base for supporting the bowl in its lowermost or normal "down" position, and suitably coordinated ways and means for satisfactorily and effectively flushing and emptying said bowl.

Another and more specific phase of the invention has to do with the adoption and use of a bowl possessed of individual shape and appearance in order to provide a desirable water trap and seal, the trap and associated flushing means being disposed and located on one longitudinal side of the bowl, whereby to permit said bowl to be elevated in relation to the base, disposed in a position overlying the mattress of a bed, and adjusted with requisite nicety and safety to a usable position practicable and convenient for a bedridden patient.

Novelty is also predicated upon a bowl which can be placed over the mattress of a bed to take the place of a bed pan, the mouth thereof being provided with an integral water-circulating and distributing flush-rim, the under side of said bowl being so fashioned and designed as to properly and satisfactorily coact with the mattress, and

2

means being provided whereby the bowl is tiltable laterally in respect to the longitudinal dimension of the bed to render it substantially self-leveling, as it were.

5 The foregoing are some of the outstanding and cardinal features and objects of the invention. It will be understood, however, that other aims, purposes and resulting advantages will become more readily apparent from the accompanying description, drawings and concluding claims.

10 In the accompanying drawings, wherein like numerals are employed to designate like parts throughout the various views:

Figure 1 is a side elevational view of a portable water closet constructed in accordance with the principles of the present invention and showing the same as a regular toilet ready for use when placed alongside a bed or any other convenient place in the sick room.

15 Figure 2 is a view based on Figure 1, but showing the manner in which the bowl is elevated and positioned over one edge portion of a bed mattress, where it may be conveniently used as a bed-pan by the occupant of the bed.

20 Figure 3 is a top plan view of the assemblage with the toilet seat omitted.

Figure 4 is a section on the plane of the line 4—4 of Figure 3, looking in the direction of the arrows.

25 Figure 5 is a view, partly in section and partly in elevation, showing the mechanical, manually regulated means for lifting and lowering the bowl.

Figure 6 is an enlarged fragmentary detailing 30 view, this taken approximately on the plane of the line 6—6 of Figure 3.

Briefly, and by way of introduction to the 35 detailed description, I deem it advisable to summarize the invention, structurally and functionally, as having to do with a dual purpose water closet characterized by a bodily shiftable mobile base provided with a perpendicularly raisable and lowerable flush-rim equipped bowl. The bowl is shaped internally and externally to accommodate

40 requirements for proper use in both so-called high and low positions. A flush valve equipped hose or conduit is employed to supply water, under pressure, to the bowl and said conduit is of elongated form and connects at one end with the 45 bowl and at an opposite end with a conventional source of supply. In addition, there is a second conduit connected in communication with the bowl, this by way of an intervening trap, and the 50 second conduit is, in turn, adapted for connection with a conventional soil pipe. Both conduits are

flexible and are of substantial length so as to permit the bowl and base, as a unitary assemblage, to be freely shifted about from place to place in the room and employed at selected points of vantage. Appropriate means is interposed between the base and the bowl so as to move the latter toward and from the base, this in a manner to permit the bowl to be elevated and lowered to assume predetermined low and high positions for selective use as a squat-type regulation toilet, on the one hand, and as an elevated bedpan, on the other hand.

Referring now to the drawings by distinguishing reference numerals, and reference being had primarily to the assembly views (Figs. 1 to 3, inclusive), I would direct attention first to the supporting means, generally speaking. This comprises what may be referred to as a portable base or carriage unit, the same denoted unitarily by the numeral 10. It comprises a rectangular or equivalent horizontal base plate 11, this provided on its under side with readily maneuverable and freely swiveling casters or equivalent rollers 12. Mounted rigidly at a predetermined point atop the central region of the base plate is a short pedestal-like stand 13 comprising a vertical post 14 and a fixed bowl-seating and adapter head or plate 15. This head has the general shape and curvature shown in the drawings. The purpose of the stand 13 will be brought out in the following description. The base plate is also provided with a suitable lifting and lowering device which may be conveniently referred to, generally speaking, as a jack 16, the latter arranged and constructed to attach to and raise and lower the bowl 17. As shown to advantage in Figure 5, this means 16 comprises a tubular standard 18 of predetermined dimensions, this attached to and rising from an appropriate foundation socket 19 on the base plate. The standard serves to accommodate a reciprocatory toothed rack bar 20 whose lower end 21 extends downwardly through and beyond the base plate, this as shown in Figure 1. In connection with the latter arrangement, it is to be pointed out that when the rack bar is in this "down" position, it serves to rest on the floor and steady and virtually "anchor" the entire carriage against slipping. A suitable cap 22 is mounted atop the upper end of the rack bar and is provided with an L-shaped bracket including a depending arm 23 and a horizontal companion arm 24, the latter embodying a fulcruming element 25 of general cylindrical cross-sectional form, as seen in Figure 6. The other parts associated therewith will be revealed as the description proceeds.

Reference being continued in Figure 5, it will be seen that 26 designates an appropriate gear housing or box, this to accommodate a cog 27 in mesh with the teeth of the rack bar, said cog operated by a worm 28 and said worm being controlled by an appropriately mounted and located hand crank 29.

Referring now to the aforementioned flush-type bowl 17, this is of suitable material and dimensions, the latter being somewhat standard as compared to regulation flush-type toilets. The bowl is, of course, of comparatively light weight stock but sufficiently sturdy to serve the purposes for which is here intended. It is characterized by a comparatively shallow receptacle having an ovate integral combination flush rim and seat 30 surrounding its mouth portion. The flush-rim 30 is of usual hollow form and serves as a water-circulating and distributor element 31 and the

under or inner flange is provided with suitably spaced distributing orifices or ports 32, as usual, to effectively flush the bowl. As brought out in Figure 3, it will be noted that the accessories and appliances for flushing and emptying the bowl, instead of being at one end, as is customary in water closets, are on one side, that is, to the right in Figure 3 and intermediate the longitudinal dimensions of said bowl. The preferred arrangement comprises a block-like formation, denoted at 33, the same being provided with a valved fixture 34 of any suitable type with a valve control handle 35 and a pipe connection 36 to accommodate a union 37 to which a flexible conduit, of rubber or equivalent materials, 38 is connected. This is the water supply hose or conduit and is connected at its intake end with an appropriate wall valve or supply device 39 with a regulating and cut-off valve 40. In this connection, it is to be understood that materials, and parts, are more or less standard in the structure as is called for in standard plumbing supplies, and I lay no claim to the standard parts, but only to the structural details and combinations as brought out in the attending claims.

Before describing the other appliances, I would return to Figure 4 of the drawings showing the bowl construction, from which it will be noted that the depending body portion of the so-called block or mount, that is, the portion indicated at 41 in Figure 4, cooperates with the associated underlying bend 42 in defining a water trap of more or less standard type, this for pooling the water and also maintaining the usual water seal indicated at 43. The discharge side of the water trap is provided with a nipple 43 to accommodate a relatively large soil hose or conduit 44. The latter is connected with the fitting 45 which in turn is connected with the soil pipe (not shown). It might be stated that these conduits 38 and 44 are of proper diameters and materials and lengths. This depends on the particular use to which the water closet is to be put. Thus, I do not desire to be limited to sizes, materials and proportions.

Referring further to the bowl, I desire to stress the under side formation thereof, that is to say, the left hand end portion 46 is relatively shallow, whereas the intermediate portion is of bulbous tapering form, as at 47, and merges nicely into the water trap. Thus, in end view, as shown in Figures 1 and 2, the bowl is of desired width formation, and this accounts, too, for the shape of the plate 15 on the stand on which the bowl rests when it takes the position seen in Figure 1. Primarily, however, the shape and formation of the bowl and the valve fittings and conduits on the right side is to adapt said bowl for use as a "bed pan" over the mattress 48 on the bed 49, as brought out in Figure 2.

The mount or block 33 is provided on one side with a hinging knuckle or sheath 50 (see Figs. 3, 5 and 6, particularly 6), this embracing the aforementioned fulcruming joint or element 25 carried by the lifting and lowering jack 16. Thus, the bowl is attached to the jack and the jack to the carriage. Moreover, the point of connection between the bowl and the jack is such as to allow the bowl to have tiltable and rocking motion, that is, self-leveling adjustment in a horizontal plane above and in relation to the longitudinal dimensions of the mattress 48. A stabilizing and return spring 51 is provided and connected with the arms 24 and bowl to maintain the desired normal balance.

Finally, there is an optional toilet seat 52 which is provided, this being hingedly mounted on said mount 33 and being swingable from left to right, that is, in a position outwardly beyond the margin of the said mattress when the structure is in the position seen in Figure 2.

I might add, too, that a short leg 54 (see Figs. 1 and 2) may be provided, this being rigidly attached to the gooseneck trap 42 and being adapted to rest on the base plate when the bowl is in the "down" position seen in Figure 1. This part adds to the stability of the structure, obviously.

It is a matter of common knowledge that the use of bed pans in hospitals is one of the varieties of obnoxious problems met by doctors, nurses and attendants, and yet facilities have not, as yet, been provided, to my knowledge, whereby the attendants can be geared to handle the situations with the requisite sense of proportion and nicety. The vital functions of patients, especially those who are motivated by a sense of agitated embarrassment, are elementary factors, but are nevertheless highly important to all concerned to avoid the inconveniences suffered by those who meet and try in vain to cope with them. I have considered it the part of wisdom to openly approach this subject of somewhat singular silence which is, apparently, a non-controversial subject due to the disturbed attitudes of all who are confronted by it. Thus, I have evolved a portable water closet which can be moved from place to place in a room, shoved beneath the bed when not in use, placed alongside the bed or elsewhere in the room when desired for use as a regular toilet, as seen in Figure 1, or shifted around and brought into place and employed as an elevated toilet or so-called flush-type "bed pan" when employed in the position illustrated in Figure 2 of the drawings.

Considering the anxieties of the patients and the serenity which attends a convertible, portable, multiple-purpose toilet of this type, I believe that it is of incalculable service. However, it is not the purpose of the present patent application to dwell upon commercial aspects or to cover the obvious needs and purposes of a structure of this character.

As previously pointed out, I do not consider it essential to stress the valves, cocks, hose connections and other fittings which might be considered as constituting standard hardware and plumbers' supplies. What I am interested in is that which is covered in the accompanying claims.

This carriage-supported water closet will aptly fulfill the general requirements of a room appliance of this type. It can be readily wheeled about and carted from place to place, shoved beneath the bed or into a closet to be out of the way, can be maneuvered and employed between beds, utilized alongside the bed, and what is most important, can be wheeled into position near the bed, after which the patient can swing and bring it into use and thereafter push it out of the way, as conditions require. In other words, due to the mobility of the carriage and the flexible accommodation possibilities of the hose connections, it lends itself admirably well to serve the patient and relieve nurses and attendants of what would otherwise be endless and disconcerting chores.

I desire to stress that phase of the invention which I consider to be an innovation, that is, the ready availability of the device in that it can be moved toward and from the bed at the proper elevation, swung over the bed and used, then swung

out of the way and shifted to a place where it will be positioned when not needed for use.

Further, and although the flushing facilities herein shown and described pertain to suitable hose-type conduits and supply and discharge pipes, it is obvious that, if necessary, a regular flush tank could be used. For that matter, even an overhead tank for gravity flushing would come, it is believed, within the purview of the 10 inventive concept.

It is a matter of moment too to touch upon the fact that plumbing requirements and codes, varying in different localities, will, of course, have to be complied with. I have not attempted to 15 comprehend these various contingencies because they do not necessarily enter the picture, as it were. However, I deem it advisable to mention that the discharge hose might well be wrapped with a suitable winding of a resilient coil-type, 20 this of metal or other materials, and may be of a predetermined pattern or shape to keep the hose toward the soil pipe in a definite sloping and downward inclination at all times whether the closet is in an up position over the bed or in a 25 low position as a beside-the-bed closet. And too, other fittings and facilities may be necessary. For example, it might even be required that a spring drum winding cylinder be employed for 30 keeping the hose-conduits under control at all times. My claims are to be interpreted keeping in mind these relevant factors.

Also, it will be noted (Figure 4) that the under side, part 41, of the mount provides the desired overhang which is so important in 35 concentrating and directing the outgoing flush water and minimizing undesirable splashing of the buttocks. By regulating the discharge ports and jets in the flushing rim to avoid objectionable cross-currents and by shunting and "funnelling" 40 the outgoing mass into the trap means, undesirable swirling and splashing will be virtually eliminated, much to the pleasure and comfort of the user.

It is also a matter of moment that the structure herein shown and described lends itself 45 adaptable as a substitute for an already installed toilet. For instance, it may be employed to replace a fixed toilet in a bath-room such as is provided adjacent to a bed in a hospital room; 50 and, in so doing, the already existing plumbing facilities may be used without substantial alterations, and the flexible conduits may be operatively connected to such existing facilities. Thus, the improved portable toilet may be kept in the bath- 55 room and conveniently wheeled out, when needed, into the adjoining hospital room and used either as (A) a regular toilet beside the bed, or (B) a bed-pan over the bed, or (C) replaced and used as a regular toilet in the bath-room.

60 A careful consideration of the foregoing description in conjunction with the invention as illustrated in the drawings will enable the reader to obtain a clear understanding and impression of the alleged features of merit and novelty 65 sufficient to clarify the construction of the invention as hereinafter claimed.

Minor changes in shape, size, materials and rearrangement of parts may be resorted to in actual practice so long as no departure is made 70 from the invention as claimed.

I claim:

1. In a portable water closet of the class described, a mobile carriage comprising wheel-supported base means, a stand fixedly mounted 75 on said base means and comprising a vertical

post and an adapter plate atop said post, a bowl, said bowl being adapted to fit and sit removably on said adapter plate, said bowl being provided with flushing means within convenient operating reach of the user, said bowl being further provided with a rigid depending leg adapted to rest on said base means when the bowl is in its lowermost position, and a jack structure mounted on said base means and connected with said bowl for raising and lowering same at will.

2. In a portable water closet of the class described, a portable carriage comprising a base, a stand fixedly mounted on said base and comprising an upright and an adapter plate atop said upright, a bowl, said bowl being adapted to sit removably on said adapter plate, said bowl being provided with patient-controlled flushing means within convenient operating reach of the user, said bowl being further provided with a depending leg adapted to rest on said base when the bowl is in its lowermost position, and a vertical jack structure mounted on and rising perpendicularly from said base and connected directly with the underside of said bowl for raising and lowering the bowl at will, said bowl being rockably mounted for limited tilting on the upper portion of said jack structure.

3. As a new article of manufacture and as a component part of an assemblage of the class described, a toilet bowl provided with a standard-type flushing rim, being provided on one side with a water trap, and said trap located intermediate the ends of said side, and being further provided with a mount for a valved hose, said mount being situated directly above and connected with said water trap, a toilet seat, means hingedly mounting said toilet seat on said mount, and the under side of said bowl being of downwardly and outwardly sloping bulbous form to render the bowl somewhat wedge-shaped in end elevation and such as to be conveniently inserted "wedged" between the patient and bed mattress to facilitate bed use.

4. In a dual purpose water closet construction of the class described, a bodily shiftable base, a perpendicularly raisable and lowerable commode bowl on said base, a flush valve equipped conduit for supplying water under pressure to said bowl, said conduit being of elongated flexible form and adapted to be connected to a conventional source of supply, a second conduit also connected to said bowl and adapted for connection to a soil pipe, said second conduit also being flexible, and both of said conduits being of substantial length to permit the bowl to be freely shifted about from place to place in the room and employed for use at selected points of vantage, means interposed between and connected with the base and bowl for moving the latter toward and from the base, whereby to permit said bowl to be elevated and lowered to assume predetermined horizontal low and high positions for selective use as a regular toilet on the one hand and a bed pan on the other hand.

5. A multiple purpose water closet of a portable type for use in hospitals and the like comprising portable base means, an elongated bowl adapted to serve, when in one position as a bed pan, and in another position as a regulation toilet-type commode, said bowl being horizontally arranged and positioned in substantial parallelism above said base means and being vertically movable in a perpendicular line toward and from the base means, said bowl embodying a flushing rim and trap, said bowl being further provided

with a flush valve, a flexible water supply hose connected at one end to the flush valve and adapted for connection at its opposite end to a regulation source of water supply, a bowl emptying hose, said hose being of flexible type and being connected at one end to said trap, the opposite end of said last named hose being adapted for connection with a conventional soil pipe, and lifting and lowering means interposed between

10. the bowl and base means and adapted to position the bowl in an elevated position for use over a bed as a bed pan and also adapted to lower the bowl to a predetermined low position for use as a regular toilet-type commode.

15. The structure specified in claim 5, said bowl being tiltably mounted on said lifting and lowering means for convenient handling when employed as a bed pan, and the contour of said bowl being externally such as to provide sloping surfaces and to render the bowl somewhat wedge-shaped in general design and appearance and to enable same to be conveniently tilted and properly placed with requisite nicety between the patient and the bed mattress.

20. 6. The structure specified in claim 5, said bowl being substantially ovate in top plan view and the underneath surfaces, constituting the bottom of said bowl being tapered transversely and at right angles to the longitudinal dimension and defining outwardly and downwardly sloping portions so contoured as to provide

25. 7. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

30. 8. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

35. 9. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

40. 10. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

45. 11. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

50. 12. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

55. 13. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

60. 14. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

65. 15. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

70. 16. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

75. 17. As a new product of manufacture and a component part of a portable flush-type commode structure of the class described, an elongated relatively shallow flush rim equipped bowl, said bowl being substantially ovate in top plan view and the underneath surfaces, constituting the bottom of said bowl being tapered transversely and at right angles to the longitudinal dimension and defining outwardly and downwardly sloping portions so contoured as to provide

and flush valve means mounted on said extension and cooperable with the deep side of the bowl and the underlying trap, the construction of the extension and trap being such that the trap entrance lies outwardly of the rim at said latter side and beneath said overhanging portion, whereby to prevent splashing of the buttocks of a person using the commode.

10. A dual purpose water closet of the class described comprising a portable base structure, an elongated commode bowl mounted on and movable toward and from said base structure, said bowl having a flushing rim and a water trap, a valved water supply hose operatively connected to said bowl and communicating with the latter by way of said flushing rim, a bowl emptying and discharging hose connected with said trap, said discharging hose being adapted for connection with a soil pipe, and a stationary stand of predetermined vertical height fixedly mounted on said base structure for coaction with the bottom of the bowl to steady and maintain same in a low regular toilet position.

11. A dual purpose water closet of the class described comprising a portable base structure, an elongated commode bowl mounted on and movable toward and from said base structure, said bowl having a flushing rim and a water trap, a valved water supply hose operatively connected to said bowl and communicating with the latter by way of said flushing rim, a bowl emptying and discharging hose connected with said trap, said discharging hose being adapted for connection with a soil pipe, and a stationary stand of predetermined vertical height fixedly mounted on said base structure for coaction with the bottom of the bowl to steady and maintain same in a low regular toilet position, together with bowl hoisting and lowering means on said base structure and connected with said bowl for hoisting the latter from said stand and then up to a position where it may be situated alongside and over a bed mattress to be used as a bed-pan by a bedridden patient.

12. In a water closet of the class described, a portable support, an elongated commode bowl, means operatively mounting said bowl on said support, said bowl being provided with a laterally inturned marginal water delivering, circulating and bowl-flushing rim; a lateral, block-like mount formed on one longitudinal side of said bowl and situated at a point intermediate the end portions of said bowl, said mount having a passage communicating with said rim and the underneath portions thereof being fashioned into a discharge equipped anti-splash trap.

13. In a water closet of the class described, a portable support, an elongated commode bowl, means operatively mounting said bowl on said support, said bowl being provided with a laterally inturned marginal water delivering, circulating and bowl-flushing rim; a lateral, block-like mount formed on one longitudinal side of said bowl and situated at a point intermediate the end portions of said bowl, said mount having a passage communicating with said rim and the underneath portions thereof being fashioned into a discharge equipped anti-splash trap, the top of said mount being flat and in a plane with said rim and thus being adapted to serve as a suitable foundation for a side attached hinging toilet seat and a hose accommodating flush-valve structure.

14. As a new article of manufacture and as a component part of an assemblage of the class described, a bowl provided with a standard-type

integral patient-seating and bowl-flushing rim, a trap provided on one side of said bowl, said trap being located intermediate opposite transverse ends of said bowl, said trap embodying a lateral outstanding mount, said mount being adapted to accommodate and support a side-hinged toilet seat and flush valve and hose means, said mount being located directly above and connected with said water trap, and a toilet seat hingedly fastened on said mount and swingable in a direction at right angles to the longitudinal axis of said bowl.

15. In a dual purpose water closet construction of the class described, a bodily shiftable base, a perpendicularly raisable and lowerable flush-rim equipped bowl, a pedestal means on said base interposed between the base and the bowl and adapted to support the bowl when the latter is in a low position for use, a flush valve equipped conduit for supplying water under pressure to said bowl by way of said flush rim, said conduit being of elongated flexible form and adapted to be connected to a conventional source of supply, fecal matter and flush-water discharge means provided in said bowl, a second conduit connected to said discharge means and adapted for connection with a soil pipe, said second conduit also being flexible, and both of said conduits being of substantial length to permit said base and bowl to be freely shifted from place to place in the room and employed for use at selected points of vantage, and mechanical means having coacting parts connected with said base and bowl respectively for raising and lowering the bowl, whereby to permit said bowl to be elevated and lowered to assume predetermined horizontal low and high positions for selective sitting and bed usage.

16. A portable dual purpose water closet adapted to be substituted for and to replace a standard-type toilet and usable within the confines of a bath-room as a regular toilet, usable as a regular toilet outside of the bath-room and beside a bed, and further usable as a bed-pan when placed over and above a bed and comprising a portable bodily movable base having relatively fixed pedestal means, a bowl resting normally and firmly on said pedestal means and occupying a plane which facilitates its use by one in a customary sitting posture, said bowl being liftable from said pedestal means and then capable of use as a bed-pan, a conduit for supplying water under flushing pressure to said bowl, said conduit being operatively connected to the bowl and being adapted for connection with a conventional source of water supply, a bowl emptying conduit connected with the bowl and adapted for connection to a conventional soil pipe, both of said conduits being of flexible form and of substantial length to permit the base and bowl to be freely shifted from place to place, means on said bowl and operable by the user for controlling the operation and use of said water supply conduit, and flush rim and toilet seat means embodied in said bowl.

17. As a new article of manufacture as well as a component part of a portable flush-type commode of the class described, an elongated relatively shallow flush-rim equipped bowl provided on one longitudinal side and at a point intermediate opposite transverse ends with a water trap, further provided with supporting means situated above said trap, said supporting means having a water passage communicating with said flush rim, water inlet means on said supporting means connected with said pas-

sage and adapted to supply water under pressure to the bowl by way of said flush-rim, water control means on said supporting means and co-operable with said water inlet means, means connected with said trap for emptying the trap into a soil pipe, a toilet seat conforming in shape to the flush rim on said bowl, said toilet seat being hingedly attached on one side intermediate its ends to said supporting means, whereby to permit said toilet seat to swing toward and from the bowl in directions at right angles to the longitudinal axis of the bowl.

18. In a dual purpose portable flush-type water closet construction of the class described, supporting means, a raisable and lowerable commode bowl operatively associated with said supporting means, said bowl being of elongated form and having a marginal discharge opening on one side for effluent passage of fecal matter and flush water, and further provided with an internal water receiving, circulating and bowl flushing rim, said rim having flush water issuing ports located to concentrate and direct the water jets toward and through said discharge opening, a conduit connected with and for supplying water under flushing pressure to said rim, said conduit being of elongated flexible form and adapted to be operatively connected to a conventional source of water supply, a second conduit also operatively

connected at its intake end to said discharge opening and adapted for operative drainage communication with waste means, said second conduit also being flexible, both of said conduits being of substantial length to permit the bowl to be lifted freely and bodily shifted about from place to place, and mechanical means interposed between said bowl and supporting means and embodying parts physically associative with said bowl and base respectively, said means being adapted for raising, lowering and/or positioning said bowl over a bed and for lowering said bowl to a regular toilet level, whereby it may thus be used as a bed-pan in the raised position and as a regular toilet in the lowered position.

ISADORE LEVIN.
